MOLD FOR CHOPPED MEAT PRODUCT

Paul F. Ruhan, Eben St., Milford, Mass. 01757

Filed Feb. 3, 1972, Ser. No. 223,410

Term of patent 14 years

Int. Cl. D7—04

U.S. Cl. D7—43

FIG. 1

FIG. 2

FIG. 3

FIG. 4

FIG. 1 is a plan view of a mold for chopped meat product showing my new design.

FIG. 2 is a side elevation thereof, the side opposite being identical thereto.

FIG. 3 is an elevational view of the upper end thereof.

FIG. 4 is an elevational view of the lower end of the mold shown in FIG. 1.

The design outlined within the mold shown in FIG. 1 is an opening extending entirely through said mold.

I claim:

The ornamental design for a mold for chopped meat product, as shown and described.
